UNITED STATES PATENT OFFICE.

OTTO W. F. POSSELT, OF NEW YORK, N. Y.

COLLAPSIBLE UMBRELLA.

Application filed March 1, 1922. Serial No. 540,207.

To all whom it may concern:

Be it known that I, OTTO W. F. POSSELT, a citizen of the United States, and a resident of New York, in the county of New York and State of New York, have invented a new and useful Improvement in a Collapsible Umbrella, of which the following is a specification.

My invention relates to collapsible umbrellas and its principal object is to provide a collapsible umbrella embodying a casing into which the umbrella is folded when not in use.

A further object of the invention is to provide an umbrella having a casing or receptacle carried by one end of the staff of the umbrella so that when not in use the umbrella may be readily collapsed and entirely enclosed within the receptacle.

It is also an object of the invention to provide an umbrella of this character which will not be cumbersome to carry when set up or in operative position and when not in use may be stored in a comparatively small space.

With the preceding and other objects and advantages in mind, the invention consists of the novel combination of elements, construction and operations to be hereinafter specifically referred to, claimed and illustrated in the accompanying drawings wherein:

Figure 1 is a side elevation of my improved umbrella in operative position.

Fig. 2 is a view of the umbrella enclosed in the casing, partly in elevation and partly in section.

Fig. 3 is a top plan view of the casing or receptacle with the cover thereof removed, and

Fig. 4 is a horizontal sectional view taken on line 4—4 of Fig. 1.

Referring to the drawing in detail, wherein corresponding characters of reference denote corresponding parts throughout the several views, the numeral 5 designates a cylindrical casing formed of any resilient material such as light steel and having the upper end thereof open, this end being formed with a circumferential bead 6.

This casing 5 is formed with spaced longitudinal slits 7 from a point adjacent its horizontal center to the open end thereof to afford a plurality of resilient arms 8. As shown in Fig. 3 each pair of the slits 7 are cut on divergent lines so that the arms 8

may be moved inwardly relative to each other to assume the same position shown in Fig. 1 and to allow these arms to interfit with each other when the casing or receptacle is in open position. In order to prevent the arms 8 from moving or springing outwardly too far, resilient bands 10 are disposed within the casing 5 and attached to the arms as indicated at 11.

An umbrella is designated at 12 and includes a handle formed of telescopic sections 13, the lower one of which being disposed centrally within the casing 5 or receptacle and threadedly engaged with a boss 14 formed upon the bottom of this receptacle. As shown in Figs. 1 and 2, the ribs of the umbrella are provided with hinged joints 15 to permit the ribs to be folded upon themselves when the umbrella is to be collapsed or telescoped into the casing or receptacle 5.

In order to cause the upper ends of the arms 8 to hug the umbrella staff when the latter is in set up position, a rubber disk 16 is provided which is fixed to one of the sections 13 and formed with an annular flange adapted to engage the beading 6 and hold the arms against springing outwardly as shown in Fig. 1.

A pliable cone-shaped cover 18 for the open end of the receptacle or casing 5 is mounted upon the umbrella 12 and is adapted to engage the bead 6 when the umbrella is received within the housing or receptacle 5.

It is to be understood that the form of my invention herein shown and described is to be taken as a preferred example of the same, and that various changes in the shape, size and arrangement of parts may be resorted to without departing from the spirit of the invention or the scope of the subjoined claims.

Having thus described my invention, what I claim as new and desire to secure and protect by Letters Patent of the United States is:

1. An umbrella including a receptacle having an open end and provided with a plurality of longitudinal slits to afford a plurality of resilient arms, the umbrella including a telescopic staff supported centrally within said receptacle and adapted to be folded within the latter, an element carried by the staff and adapted to engage the upper ends of the arms to hold the same into hugging engagement with the staff, and a

closure carried by the umbrella for closing the open end of the receptacle when the umbrella is collapsed therein.

2. An umbrella including a casing open at its upper end and provided with a plurality of longitudinal slits to provide resilient arms, a collapsible umbrella supported within the casing and adapted to be folded within the same when not in use, an element 10 for holding the resilient arms into hugging engagement with the umbrella staff when it is in operative position, and a closure carried by the umbrella for closing the open end of the receptacle.

15 3. In a collapsible umbrella, a casing formed of resilient material and having the upper end thereof open, an umbrella including a staff supported centrally within the casing, means for causing the upper end of 20 the casing to hug the staff when the umbrella is in operative position, and a pliable closure carried by the umbrella for engaging the upper end of the casing when the umbrella is received therein.

25 4. An umbrella including a tubular casing

formed of light resilient material and provided with a plurality of longitudinal slits to afford resilient arms, a collapsible umbrella supported within the casing and capable of being entirely housed within the 30 same and adapted to be withdrawn therefrom an element carried by the umbrella staff for engaging the upper ends of the arms to hold the same inwardly, and a conical closure carried by the umbrella and 35 adapted to engage the upper end of the casing.

5. An umbrella including a tubular casing formed of light resilient material and provided with a plurality of longitudinal slits 40 thereby affording resilient arms, a collapsible umbrella supported within the casing and capable of being entirely housed within the same and adapted to be withdrawn therefrom, resilient bands secured to the inner 45 face of the arms and a closure carried by the umbrella and adapted to engage the upper end of the casing when the umbrella is enclosed therein.

OTTO W. F. POSSELT.
